UNITED STATES PATENT OFFICE.

LEWIS P. HALLADAY, OF STREATOR, ILLINOIS.

PHONOGRAPH-HORN SUPPORT.

No. 857,169.

Specification of Letters Patent.

Patented June 18, 1907.

Application filed January 16, 1907. Serial No. 352,538.

To all whom it may concern:

Be it known that I, LEWIS P. HALLADAY, a citizen of the United States, residing at Streator, in the county of LaSalle, State of Illinois, have invented a certain new and useful Improvement in Phonograph-Horn Supports, of which the following is a specification.

My invention relates to phonograph horn supports and it is illustrated in the accompanying drawing wherein the figure shows an end and part sectional view of a phonograph apparatus containing my invention.

In the drawing A is the case from which the cover and phonograph mechanism have been removed.

B is the top of the case projecting preferably at B¹ and B².

C is an arm which preferably lies across the top of the case and is hooked at C¹ to engage the part B². This arm is upwardly turned at C² to carry the supporting ring C³ for the sound conveyer C⁴ and the horn C⁵. The details of this part of the mechanism are not further here described.

Downwardly projecting from the arm C is the part D through which passes the screw D¹ having the thumb piece D². The inner end of the screw D¹ carries the clamping block E which is provided with a curved face to engage the edge B¹ of the table top. By thus providing the horn support proper, or

upward portion C², with a clamping device which bears on both sides of the case or the lid so as to distribute the weight of the horn 35 around the case, I am able to get great strength and have a horn support which will be self contained. The weight of mechanism comes over the middle of the case, or at least is carried by the top of the case and the 40 weight of the horn on the part which supports it is thus thrown under the weight of the mechanism.

I claim:

As a new article of manufacture, a phonograph horn support comprising a rigid arm provided at one end with an outer hook shaped portion to clasp the edge of the table and adapted to extend across the box, and having an upwardly projecting portion at 45 the other end thereof carrying a horn supporting ring, a threaded sleeve on the bottom of the arm beneath the upwardly projecting portion, a horizontally arranged screw threaded rod working therein, and a clamp 50 on the inner end of the rod adapted to engage the edge of the top of the table opposite the edge engaged by the hook, substantially as described.

LEWIS P. HALLADAY.
